(57) **ABSTRACT**

'WH02' is a hybrid dessert banana variety with a tall stature, is tolerant to Black Sigatoka, and produces high-quality fruit.

6 Drawing Sheets

1

Latin name of the genus and species of the plant claimed: This triploid plant has only *M. acuminata* in its pedigree and is the product of an inter-specific cross between the triploid (AAA) cultivar 'Williams' and 'Highgate' ('HG'). Its Latin name is *M. acuminata* (AAA) group, representing three genomes of this genus and species.

Variety denomination: 'WH02'.

CROSS-REFERENCE TO RELATED APPLICATIONS

This application is co-pending with the following additional applications by the same inventor: "DESSERT BANANA PLANT NAMED 'SH-4199'" (application Ser. No. 18/469,772), "DESSERT BANANA PLANT NAMED 'WW01'" (application Ser. No. 18/469,766), "DESSERT BANANA PLANT NAMED 'NW02'" (application Ser. No. 18/469,776) and "DESSERT BANANA PLANT NAMED 'HG07'" (application Ser. No. 18/469,787). The plants of these applications, as well as the plant of the present application, were created in the banana breeding program of Applicant/Owner/Assignee, FHIA.

STATEMENT REGARDING FEDERALLY SPONSORED RESEARCH OR DEVELOPMENT

Not applicable.

BACKGROUND OF THE INVENTION

1. Field of the Invention

This invention relates to a new and distinctive hybrid banana variety named 'WH02'. This new hybrid variety was the result of a field cross performed in 2016 in La Lima Cortés, Honduras, between 'Williams' x 'Highgate' ('HG') (Both unpatented). 'HG' is a triploid plant (AAA) susceptible to Black Sigatoka leaf spot disease (*Mycosphaerella fijiensis*) and *Fusarium oxysporum* race 1, belonging to the

2

Gros Michel group. 'Williams' is a medium-sized triploid plant (AAA) susceptible to Black Sigatoka leaf spot disease and resistant to *Fusarium Oxysporum* race 1 but susceptible to race 4, belonging to the Cavendish group. 'Williams' is one of the most commercialized bananas worldwide; people prefer it for its flavor, aroma, and size. Both banana varieties were selected from a germplasm collection.

'WH02' is a triploid hybrid (AAA) created for the genetic improvement of the Gros Michel banana group. This hybrid was selected in 2018 from several first-generation seedlings 10 from the cross between 'Williams' x 'HG'. It was chosen as a triploid hybrid, maintaining characteristics of its parent's lines and producing bunches of 18 kilograms. 'WH02' was asexually reproduced by corms by the breeder in La Lima Cortés, Honduras. All plants and fruit run true to the initially selected plant and are identical in all aspects.

The 'WH02' hybrid shares many characteristics with its parent plants, 'Williams', and 'Highgate'. It has a similar leaf shape, plant height, and stem shape. However, the bunch shape is quite different from its parents, and the flavor is 20 slightly altered as well. While 'Williams' and 'Highgate' are both sweet and have a pleasant flavor, the 'WH02' hybrid is slightly sweeter with a unique taste. Unfortunately, like its parents, it is highly susceptible to black Sigatoka (*Mycosphaerella fijiensis*), a disease that affects banana plants. It's important to note that this comparison is made in the context of commercial varieties, as 'Williams' is one of the most widely commercialized banana varieties in the world 25 and, a parent of this hybrid.

BRIEF SUMMARY OF THE INVENTION

'WH02' is a hybrid dessert banana variety with a tall stature, is tolerant to Black Sigatoka, and produces high-quality fruit.

BRIEF DESCRIPTION OF THE PHOTOGRAPHS

The figures describe the characteristics of the 'WH02' hybrid banana variety at 10.5 months old. The color shown

in the photographs is as nearly accurate as reasonably possible in this type's color representation.

FIG. 1 shows the typical appearance of a plant;

FIG. 2A-B shows blotches at the petiole base (A) and a petiole canal leaf (B);

FIG. 3A-C shows the shape of a leaf blade base (A) and leaf upper (B) and leaf lower (C) surfaces;

FIG. 4 shows typical suckers;

FIG. 5 shows a typical fruit bunch;

FIG. 6 shows a male bud;

FIG. 7A-C shows bracts of a male bud;

FIG. 8A-B shows compound tepal (A) and free tepals (B) lobes;

FIG. 9A-B shows style shape (A) and ovary (B);

FIG. 10 shows a typical male flower;

FIG. 11 shows rowed ovules and

FIG. 12 shows a typical second hand.

DETAILED BOTANICAL DESCRIPTION

This report provides a thorough botanical description of the new 'WH02' variety evaluated in La Lima, Cortés, Honduras, 2023. The descriptions concord with the internationally standardized "Descriptors for Banana (*Musa* spp.)" elaborated by IPGRI/INIBAP/CIRAD, 1996 (www.inibap.org), and The U.K.'s Royal Horticultural Society's Colour Chart, 2001. The 'WH02' plant and its fruit may differ slightly from the descriptors provided due to variations in cultural practices, soil types, and climatic conditions under which the variety may be cultivated.

Leaf habit	Intermediate
Dwarfism	tall
Pseudostem height	≥3 meters
Pseudostem length	2.46 m
Pseudostem diameter	61 cm
Pseudostem aspect	Robust
Pseudostem color	Green (141C, RHS)
Pseudostem appearance	Shiny (not waxy)
The predominant underlying color of the pseudostem	Yellow-Green (150D, RHS)
Pigmentation of the underlying pseudostem	Greyed-Purple (187B, RHS)
Sap color	Watery (155D, RHS)
Wax-on leaf sheaths	Very few waxes
Number of suckers	4
Development of suckers	>3/4 of the height of the parent plant
Position of suckers	Close to parent (vertical growth)
Blotches at the petiole base	Small blotches
Blotches color	Grey-Brown (N196A, RHS)
Petiole canal leaf III	Wide with erect margins
Petiole margins	Winged and clasping the pseudostem
Wing type	Dry
Petiole margin color	Without color
Edge of petiole margin	Colourless (Without a color line along)
Petiole margin width	1 to 2 cm
Leaf blade length	171 to 220 cm
Leaf blade width	81 to 90 cm
Petiole length	45 to 50 cm
Color of the leaf's upper surface	Green (137A, RHS)
Appearance of leaf upper surface	Dull
Color of the leaf's lower surface	Green (N139B, RHS)
Appearance of leaf lower surface	Dull
Wax on leaves	Few waxes

-continued

5	Insertion point of leaf blade on petiole	Symmetric
5	Shape of the leaf blade base	Both sides rounded
5	Leaf corrugation	Even, smooth
5	Color of midrib dorsal surface	Green (138B, RHS)
5	Color of midrib ventral surface	Yellow-Green (145C, RHS)
5	Color of cigar leaf dorsal surface	Green (139C, RHS)
10	Blotches on leaves of water suckers	Without blotches
10	Peduncle length	61 to 68 cm
10	Empty nodes on the peduncle	Two or more
10	Peduncle width	7-12 cm
10	Peduncle color	Green (137B, RHS)
10	Peduncle hairiness	Very hairy, short hairs (similar to velvet touch)
15	Bunch position	Hanging vertically
15	Bunch shape	Cylindrical
15	Bunch appearance	Lax
15	Bunch length	120 cm
15	Bunch diameter	66 cm
20	Number of hands of the bunch	12
20	Flowers that form the fruit	Female
20	Fruits	Biseriate
20	Rachis type	Present and male buds may be degenerated or persistent.
25	Rachis position	With a curve
25	Rachis appearance	Bare
25	Male bud type	Normal (present)
25	Male bud shape	Like a top
25	Male bud size	31 cm
25	Bract base shape	Large shoulder
25	Bract apex shape	Pointed
30	Bract imbrication	Old bracts overlap at the apex of the bud.
30	Color of the bract external face	Greyed-Orange (177D, RHS)
30	Color of the bract internal face	Yellow (10D, RHS)
30	Color of the bract apex	Tinted with yellow (discolored) (7C, RHS)
35	Color stripes on the bract	Without discolored lines or stripes on the external face
35	Bract scars on rachis	Very prominent
35	Persistence of the bracts of the rachis	Moderate
35	Fading of color on bract base	Color discontinuing towards the base.
40	Male bract shape	Ovate
40	Male bract lifting	Lifting one at a time
40	Bract behavior before falling	Revolute (Rolling)
40	Wax on the bract	Moderately waxy
40	Presence of grooves on the bract	Moderate
45	Male flower behavior	Falling after the bract
45	Compound tepal basic color	White (155C, RHS)
45	Compound tepal pigmentation	Very few or no visible signs of pigmentation
50	Lobe color of compound tepal	Greyed-Orange (163B, RHS)
50	Lobe development of compound tepal	Developed
50	Free tepal color	Opaque White (155D, RHS)
50	Free tepal shape	Oval
50	Free tepal appearance	Simple folding under the apex
50	Free tepal apex development	Little or no visible sign of development
55	Free tepal apex shape	Thread-like
55	Anther exertion	Inserted
55	Filament color	Greyed-White (156D, RHS)
55	Anther color	Green-White (157C, RHS)
55	Pollen sacs color	Greyed-Red (198D, RHS)
55	Pollen vitality	Medium
60	Style basic color	Green-White (157C, RHS)
60	Pigmentation on style	Without pigmentation
60	Style exertion	Inserted
60	Style shape	Curved at the base
60	Stigma color	Yellow-Orange (14A, RHS)
60	Ovary shape	Arched
65	Ovary basic color	Green (142D, RHS)

US PP36,098 P2

5

-continued

Ovary pigmentation	Very few or no visible signs of pigmentation
Dominant color of male flower	White 155C, RHS)
Irregular flowers	Absent
Arrangement of ovules	Two rowed
Fruit position	Parallel to the stalk
Number of fruits	17 to 20
Fruit length	13 to 15 cm
Fruit width	3.2 cm
Fruit shape (longitudinal curvature)	Curved (sharp curve)
Color of the flesh of the fruit	Creamy (158C, RHS)
Longitudinal ridges of the fruit	Moderate
Transverse section of fruit	Slightly ridged
Fruit apex	Blunt-tipped
Remains of flower relicts at the fruit apex	Persistent style
Fruit pedicel length	21 to 23 mm
Fruit pedicel width	5 to 10 mm
Pedicel surface	Hairy

6

-continued

Fusion of pedicel	Very partially or no visible sign of fusion
5 Immature fruit peel color	Green (141D, RHS)
Mature fruit peel color	Yellow-Orange (14C, RHS)
Fruit peel thickness	2 to 3 mm
Adherence to the fruit peel	Fruit peels easily
Cracks in fruit peel	Cracked
Pulp in fruit	With pulp
Pulp color before maturity	White (N155D, RHS)
10 Pulp color at maturity	Yellow-Orange (18B, RHS)
Fruits fall from hands.	Deciduous
Flesh texture	Firm
Predominant taste	Sweet (like Cavendish)
Presence of seed with the source of pollen	Without seeds
15 Seed surface	Without seeds
Seed shape	Without seeds
Growth habit of the plant	Upright

The invention claimed is:

20 1. A new and distinct variety of banana plant named 'WH02', substantially as illustrated and described herein.
